UNITED STATES PATENT OFFICE.

WILLIAM W. RONEY, OF SEWICKLEY, PENNSYLVANIA, ASSIGNOR TO ASBESTOS PROTECTED METAL COMPANY, OF PITTSBURGH, PENNSYLVANIA, A CORPORATION OF PENNSYLVANIA.

APPARATUS FOR FORMING PROTECTED METAL SHEETS.

1,277,758.

Specification of Letters Patent.

Patented Sept. 3, 1918.

Application filed February 23, 1918. Serial No. 218,749.

To all whom it may concern:

Be it known that I, WILLIAM W. RONEY, a citizen of the United States, and a resident of Sewickley, in the county of Allegheny and 5 State of Pennsylvania, have invented an Improvement in Apparatus for Forming Protected Metal Sheets, of which the following description, in connection with the accompanying drawings, is a specification, like 10 characters on the drawings representing like parts.

This invention relates to apparatus for the manufacture of protected metal sheets in which protecting layers of fibrous material, 15 preferably asbestos paper, are adhesively affixed to the metallic sheets.

The invention has for its object to provide a simple and efficient apparatus for the manufacture of protected metal sheets having 20 separate layers of fibrous material adhesively affixed to the opposite surfaces of each metallic sheet, and having the side edges of the latter enveloped by folded over portions of one or both of said fibrous layers, 25 which folded over portions overlap one or both fibrous layers, as will be described.

To this end, the machine is provided with means for coating the metal sheet with adhesive material, and with means for applying the separate fibrous layers to the opposite surfaces of the coated sheet, so that preferably both fibrous layers project beyond a side edge of the metal sheet to form side flaps, and further with mechanism for folding 35 the side flaps in opposite directions and over the opposite side edges of the metal sheet and substantially parallel with the latter.

The folding mechanism has coöperating 40 with it means for guiding the covered metal sheet and for pressing the folded over flap of one fibrous layer against the other fibrous layer. The folding mechanism also has coöperating with it means for drawing in the 45 folded over flap so as to produce a tight fold over the side edges of the metal sheet.

These and other features of the invention will be pointed out in the claims at the end of this specification.

50. Figure 1 represents an elevation of a machine embodying this invention.

Fig. 1^a, a section on line 1^a—1^a, Fig. 2.

Fig. 2, a plan and Fig. 3 a side elevation of the folding mechanism.

Fig. 4 an enlarged section on line 4—4, 55

Fig. 2, looking in the direction of the arrows, and

Figs. 5, 6 and 7 enlarged elevations of the individual folding rolls in different stages 60 of operation.

Referring to the drawings, which illustrate one form of machine embodying this invention, 10 is a suitable receptacle containing an adhesive material 12, and through which extend guides or runways 13 for metallic sheets 14, which are fed in a continuous manner by suitable feed rolls, represented by the gears 15, 16, from a suitable feeding table 17, into the receptacle 10. The adhesive material 12 may and preferably 65 will be of a bituminous composition and maintained in a molten condition by suitable heating means, one form of which is shown herein as the gas burner 30 applied to the receptacle 10. 70

The metallic sheets 14 travel in succession and preferably spaced a short distance apart, 75 through the guides 13 in the receptacle 10, where they are coated upon all surfaces with the adhesive material 12, and are then conducted to a position where they are gripped by combining rolls represented by the gears 18. At this point the fibrous layers 19, 20, preferably asbestos paper, having been pre-threaded up through the combining rolls 18, 80 and coming from the supply rolls 21, 22, are applied to the opposite surfaces of the successive metallic sheets as the latter pass between the fibrous layers 19, 20 on their upward travel, and are affixed thereto by the 85 adhesive coating on the metal sheet. The machine thus far described is substantially 90 that shown and described in U. S. Patent 1,002,303 dated Sept. 5, 1911.

The supply rolls 21, 22, are rendered laterally adjustable in their bearings in any suitable manner, as for instance by providing the supporting mandrels 23, 24, with suitable threads, which are adapted to engage similar threads in their bearings 25, 26, so 95 that rotation of the mandrels 23, 24, by suitable means as for instance by the cranks 27, 28, causes the said mandrels and rolls supported thereby to be moved laterally. 100

By means of this lateral adjustment of the supply rolls 21, 22, the application of each fibrous layer to the coated metal sheet may be effected, so that upon each surface 5 of the metal sheet the fibrous layer will extend from a point substantially flush with one side to a point beyond the opposite side of the said metal sheet.

The sheet in this form travels from the 10 combining rolls 18 over the guide rolls 30, 31, and is then drawn preferably in a substantially horizontal position through a folding mechanism to be hereinafter described, by draw rolls 32, and then passes 15 over the guide rolls 33 and is received upon trucks or other receiving devices.

The exact position of the folding mechanism with respect to the combining rolls 18, may be varied from the position illustrated 20 in Fig. 1 as desired without departing from the invention. The coating of adhesive material which the metal sheet receives upon passing through the bath 10, is of such thickness that when the fibrous layers are 25 affixed thereto by the combining rolls 18, enough adhesive material is squeezed out by the pressure of the said combining rolls to coat one surface of the projecting side portions or flaps 34, 35, of the fibrous layers 30 19, 20, see Fig. 4, so that upon subsequent folding of said flaps by the folding mechanism, the flaps are adhesively secured to the body portion of the sheet.

The folding mechanism referred to is preferably made as herein shown and consists of two sets of rolls, spaced apart and arranged to coöperate with the flaps at the opposite sides of the metal sheet. Each set of rolls comprises a plurality of rolls herein 40 shown as four in number, which are adjustable to any desired position with respect to the edge of the metal sheet as will be described.

Each set of folding rolls consists as herein 45 shown of four beveled or grooved rolls 40, 41, 42, 43, see Figs. 2 and 3, and the endmost rolls 40, 43, of said sets, are arranged on opposite sides of the path of movement of the metal sheet and have coöperating with 50 them guiding and pressing devices, preferably rolls 44, 45 provided with circular peripheries. Each of the pressure rolls 44, 45, is loosely mounted upon a shaft 46, see Fig. 4, and each of the folding rolls is loosely 55 mounted upon a shaft 47 which has bearings in the forked member 48 of a shaft 49.

The shafts 46, 49, are mounted in supporting members or blocks 50, 51, carried by a supporting frame, which is herein shown as 60 substantially parallel rods 52, 53, supported by blocks 54, 55 mounted on rods 56, 57, extended substantially at right angles to the rods 52, 53. The rods 56, 57 are shown as vertically arranged and the rods 52, 53 as 65 horizontally arranged, and the blocks 54, 55,

are slidable on the vertical rods 56, 57, so as to adjust the horizontal rods 52, 53, toward and from each other, and thereby adjust the rolls carried by the said horizontal rods toward and from the path of movement 70 of the metal sheet. The blocks 54, 55, may be secured in their adjusted positions on the vertical rods 56, 57, by set screws 58 or otherwise.

The blocks 50, 51 are adjustable on the 75 horizontal rods 52, 53, in different directions, being capable of movement lengthwise of the rods and also capable of turning or rotating thereon, and said blocks may be secured in their adjusted positions by set 80 screws 59 or otherwise. The shafts 46, 49, are also capable of adjustment in the blocks 50, 51, being movable lengthwise thereon and also rotatable therein, and they are secured in their adjusted positions in said 85 blocks by set screws 60 or otherwise.

The vertical rods 56, 57, are erected upon suitable bases 61 and provision is made for adjusting the supporting framework at opposite sides of the metal sheet toward and 90 from each other, which is accomplished as herein shown by means of screw threaded rods 62 extended through the opposing bases 61, each of said rods having nuts 63, see Fig. 4, which engage one side wall 65 of each base 95 and coöperate with springs 66 encircling said screw threaded rods between the nuts 63 and the opposite side walls 67 of said bases. The bases 61 are guided in their movement by rods 68 extended through them and supported by suitable blocks or uprights 69, only one of which is shown in Fig. 4. It will thus be seen, that the folding and guiding rolls are capable of adjustment lengthwise of their supporting frames, and also 100 are rotatably adjustable about the horizontal rods 52, 53, and further they are axially and lengthwise adjustable in their bearing blocks. These various adjustments permit 105 the individual rolls to be adjusted to practically any desired position with respect to the edge of the metal sheet. The supporting frames are capable of being adjusted toward and from each other by turning the screw rods 62, and are capable of automatic 110 adjustment to compensate for moderate variations in the widths of the metal sheets by means of the springs 66, which permit the bases to move on the guide rods 68 away from the sides of the metal sheet, the spring 115 66 being compressed between the side wall 67 of the base and the nut 63.

In the present instance, the fibrous layers 19, 20, are applied to the coated metal sheet 14 so that the upper layer 19 projects beyond 120 one edge of the metal sheet and the lower layer 20 beyond the opposite edge thereof, and the folding rolls at the opposite sides of the path of movement of the metal sheet are arranged so that the flap 34 of the upper 130

layer 19 will be turned down and under the metal sheet, and the flap 35 of the lower layer 20 will be turned up and over upon the metal sheet, the said flaps being cemented to the fibrous layers 20, 19, respectively, by the surplus adhesive squeezed out from between the fibrous layers and the metal sheet. The action of the sets of folding rolls shown in Figs. 1 and 2, is clearly illustrated in Figs. 4 to 7. Referring to Fig. 5, it will be seen that one bearing surface 70 of the folding roll 40 is parallel or substantially parallel with the metal sheet and bears upon the fibrous layer 19 upon the upper surface thereof, while the other bearing surface 71 of said roll extends at an angle to the sheet and below the same, in which position it engages the flap 34 and turns the latter down, from which position it is turned into a substantially vertical position by the bearing surface 71 of the next adjacent roll 41, see Fig. 6. As the metal sheet is carried farther forward in the direction of the arrow 72 in Fig. 2, the flap 34 is turned partially under the metal sheet by the bearing surface 71 of the next roll 42, see Fig. 7, and is then completely folded under and brought into a position parallel with the metal sheet and in engagement with the fibrous layer 20 by the bearing surface 71 of the roll 43, see Fig. 4. The flap 35 on the lower layer 20 is folded in the reverse direction and the folding rolls coöperating therewith are reversely arranged with respect to the folding rolls coöperating with the flap 34 as represented in Fig. 2.

The final folded position of the flap 35 is represented in Fig. 4. It will be understood that the folded flaps are adhesively affixed to the fibrous layers between them and the metal sheet and are pressed into engagement therewith by the coöperation of the last folding roll with the pressure and guiding roll 44 or 45. After the flaps have passed by the last set of folding and pressure rolls, it is preferred to draw them in and thus produce a tight fold over the side edges of the metal sheet. This is accomplished as herein shown by bias rolls 80, which are arranged at an angle with respect to the travel of the sheet as shown in Figs. 2 and 3, and coöperate with bearing rolls 81.

The bias and bearing rolls 80, 81, also act as pressure rolls and coöperate to firmly affix the flaps to the body portion of the sheet and said rolls may and preferably will be supported by blocks 82, 83, adjustably mounted on the rods 52, 53, of the side frames, so that the bias and bearing rolls 80, 81, may be adjusted laterally with relation to the metal sheet simultaneously with the folding and pressure rolls. It will be observed that by making the folding rolls bodily movable and independently adjustable into different angular positions with relation to the path of

movement of the metal sheet, the said rolls may be made of the same form and construction and readily positioned to effect the progressive folding desired.

I have above described one construction of apparatus embodying the invention preferred by me, but it is not desired to limit the invention to the particular construction shown. Furthermore, I have herein illustrated the invention in an apparatus arranged to fold the flaps in opposite directions but it is not desired to limit the invention in this respect.

Claims:

1. In an apparatus of the character described, in combination, a receptacle for containing adhesive material, means for conducting a metal sheet through said receptacle to coat the same with adhesive material, means for applying separate fibrous layers to opposite surfaces of the coated metal sheet, so that a portion of each fibrous layer extends beyond one side edge of the metal sheet, and beyond the edge of the fibrous layer applied to the opposite surface of said metal sheet, and means for folding the said projecting portions of the fibrous layers in opposite directions over the side edges of the metallic sheet and upon the fibrous layers affixed to the opposite surfaces of said metal sheet.

2. In an apparatus of the character described, in combination, a receptacle for containing adhesive material, means for conducting a metal sheet through said receptacle to coat the same with adhesive material, means for applying separate fibrous layers to opposite surfaces of the coated metal sheet, so that a portion of each fibrous layer extends beyond one side edge of the metal sheet, and beyond the edge of the fibrous layer applied to the opposite surface of said metal sheet, means for folding the said projecting portions of the fibrous layers in opposite directions over the side edges of the metallic sheet and upon the fibrous layers affixed to the opposite surfaces of said metal sheet, and means for pressing the folded portions against the opposite surfaces of the metal sheet.

3. In a machine of the character described, means for coating a metal sheet with adhesive material, means for applying separate fibrous layers to the opposite surfaces of the said coated sheet, so that opposite sides of the fibrous layers project beyond the opposite side edges of the coated metal sheet and beyond the edge of the fibrous layer applied to the opposite surface of said metal sheet, and means for folding said projecting portions in opposite directions around said edges and upon the fibrous layers affixed to the opposite surfaces of said metal sheet.

4. In a machine of the character de-

- scribed, means for coating a metal sheet with adhesive material, means for applying separate fibrous layers to the opposite surfaces of the said coated sheet, so that opposite 5 sides of the fibrous layers project beyond the opposite side edges of the coated metal sheet and beyond the edge of the fibrous layer applied to the opposite surface of said metal sheet, and means for folding said 10 projecting portions in opposite directions around said edges and upon the fibrous layer affixed to the opposite surfaces of said metal sheet, said folding means being adjustable to variations in the width of the metal 15 sheets.
5. In combination, means for coating a metal sheet with adhesive material, means for applying separate layers of fibrous material to the opposite surfaces of said coated 20 sheet with one of the said layers projecting beyond one side of said metal sheet and beyond the edge of the fibrous layer applied to the opposite surface of said metal sheet, and means for folding the projecting portion 25 of a layer affixed to one surface of the metal sheet over the edge thereof and upon the fibrous layer affixed to the opposite surface of said metal sheet.
6. In combination, means for coating a 30 metal sheet with adhesive material, means for applying separate layers of fibrous material to the opposite surfaces of said coated metal sheet with one of said layers projecting beyond one edge of the coated metal sheet, means for guiding said covered metal 35 sheet, and a plurality of folding devices spaced apart and bodily movable into different angular positions with relation to the path of movement of the metal sheet to progressively fold the projecting portion of one 40 fibrous layer around the edge of the metal sheet and over upon the other fibrous layer thereon.
7. In combination, means for applying 45 separate fibrous layers to opposite surfaces of a metal sheet coated with adhesive material so that fibrous flaps project beyond the opposite side edges of said metal sheet, guiding devices located on the opposite sides of 50 the path of movement of said metal sheet and coöperating with the opposite surfaces of the latter, folding devices coöperating with said guiding devices and arranged with relation to the path of movement of the 55 metal sheet to oppose said guiding devices, and intermediate folding devices arranged at different angles with relation to the path

of movement of the metal sheet and coöperating with the edge of the latter.

8. In combination, means for applying 60 separate fibrous layers to opposite surfaces of a metal sheet coated with adhesive material so that fibrous flaps project beyond the opposite side edges of said metal sheet, guiding devices for the metal sheet coöperating 65 with the opposite surfaces thereof, folding devices coöperating with the edges of the sheet to fold said flaps over the same, and bias rolls coöperating with the folded-over flaps. 70

9. In a machine of the character described, mechanism for folding the projecting portion of a fibrous layer around a side edge of a metal sheet to which it is adhesively affixed, comprising a plurality of rolls bodily 75 movable to adjust them to different stages of the folding operation.

10. In a machine of the character described, mechanism for folding opposite projecting portions of fibrous layers over the 80 side edges of a metal sheet to which they are adhesively applied, comprising substantially parallel sets of folding rolls, adjustable to variations in width of the metallic sheets, and means for simultaneously effecting the 85 adjustment of the rolls located on opposite sides of said metal sheet.

11. In combination, means for applying separate fibrous layers to opposite surfaces of a metal sheet coated with adhesive material 90 so that fibrous flaps project beyond the opposite side edges of said metal sheet, guiding devices for the metal sheet coöperating with the opposite surfaces thereof, folding devices coöperating with the edges of the 95 sheet to fold said flaps over the same, and means coöperating with the folded over flaps to draw them in from the side edges of the metal sheet and effect a tight fold over the said side edges. 100

12. In a machine of the character described, mechanism for folding the projecting portion of a fibrous layer around a side edge of a metal sheet to which it is adhesively affixed, comprising a plurality of devices bodily movable in the arcs of circles to 105 adjust them to different stages of the folding operation and means for securing said devices in different fixed positions in the arcs in which they are moved.

In testimony whereof I have signed my name to this specification.

WILLIAM W. RONEY.
